FIG. 1 is a front perspective view.

FIG. 2 is a rear perspective view.

FIG. 3 is a top plan view.

FIG. 4 is a front elevation view.

FIG. 5 is a side cross-sectional elevation at line 5—5 in FIG. 3.

FIG. 6 is a front cross-sectional elevation at line 6—6 in FIG. 3; and,

FIG. 7 is a rear cross-sectional elevation at line 7—7 in FIG. 3.

The side cross-sectional view at line 5—5 in FIG. 3 to the right would be the mirror image of FIG. 5. A bottom plan view would be devoid of surface ornamentation.
